UNITED STATES PATENT OFFICE.

FRANKLIN BUTLER CROSBY, OF SHORT HILLS, NEW JERSEY.

MERRY-GO-ROUND.

1,050,130.

Specification of Letters Patent. Patented Jan. 14, 1913.

Application filed December 3, 1909. Serial No. 531,932.

To all whom it may concern:

Be it known that I, FRANKLIN BUTLER CROSBY, a citizen of the United States, and a resident of Short Hills, in the county of 5 Essex and State of New Jersey, have invented certain new and useful Improvements in Merry-Go-Rounds, of which the following is a specification.

My invention has reference in general to 10 that class of amusement devices known as merry-go-rounds or round-a-bouts, and relates more particularly to improvements in the manner of mounting passenger carrying platforms or cars on the main structure of 15 the merry-go-round and to novel means for driving the same.

Heretofore it has been customary to construct merry-go-rounds in the form either of a single rotatable platform, on which are 20 placed passenger carrying devices fixed with relation to the main platform, or else to mount thereon smaller platforms rotatable about centrally located axes.

My improvements in the mounting of the 25 platforms and in the platform driving means have the advantage of producing unique and novel sensations on the part of the passengers, not obtainable in merry-go-rounds as thus previously constructed.

30 In the accompanying drawings, which form a part of this specification, and in which like numerals are used to represent the same parts throughout all the figures, I have illustrated only certain selected modifications of my invention, but I do not wish to be limited thereto, as it is obvious that my invention may be embodied in numerous other forms.

35 In these drawings Figure 1 is a plan view 40 of a construction embodying my invention; Fig. 2 is a sectional view on the line II—II of Fig. 1; Fig. 3 is an enlarged sectional detail showing the construction of the driving connection between the motors and the 45 individual platforms; Fig. 4 is a detail of the mounting of one of the platforms or cars showing a modification in the manner of transmitting motion thereto; Fig. 5 is a plan view of a structure similar to that 50 shown in Fig. 1, but illustrating a different mechanism for causing rotation of the individual platforms, a central gearing being used in place of the individual motors shown in Fig. 1; Fig. 6 is a sectional view 55 on line VI—VI of Fig. 5; Fig. 7 is a detail showing driving connections similar to those

illustrated in Fig. 5, with a different ratio of gears; Figs. 8 and 9 are diagrams illustrating the paths through which persons situated at different points in a car pass during the operation of the round-a-bout. 60

Describing the drawings in detail, the numeral 1 designates a platform supported by main beams or girders 2 connected near their extremities by stiffeners 3. This platform 65 is so supported that it may be rotated about its axis, any suitable supporting means being used, such for instance as the shafts 8 journaled in bearings attached to the underpinning of the main platform and carrying 70 flanged wheels 9 resting on the circular track 10. The platform may be rotated through one of the wheels 9 driven by means of a gear 11, fixed to one of the shafts 8, which meshes with a pinion 12 carried by the driving 75 shaft of a motor 13.

Upon the main platform are mounted one or more passenger carrying cars or platforms 6 which may be provided with seats 7 and which rotate about movable axes 80 spaced from the axis of rotation of the main platform. In the preferred form of my invention these cars or platforms are preferably mounted eccentrically with reference to their axes of rotation. In Figs. 1, 2 and 3 85 the cars are shown as supported upon and secured to the upper ends of sleeves 22 journaled upon shafts 5 carried by the supporting platforms 4 which are built upon the members 2 and 3 of the main rotatable plat² 90 form. The sleeves 22 and cars 6 carried thereby are rotated from motors 16 mounted on the platforms 4 through the gearing shown most clearly in Fig. 3. This gearing comprises the bevel gear 14 meshing 95 with the driving pinion 15 of the motor, and fixed to the shaft 5 which it rotates. The shaft 5 carries at its lower extremity a pinion 17 which meshes with the gear 18 on the countershaft 19, on the upper end of which 100 is mounted an elliptical gear 20. The latter meshes with and drives the companion elliptical gear 21 secured to the sleeve 22. As will be obvious, power from the motor 16 is thus transmitted through gears 15, 14, 105 17 and 18 to the shaft 19, necessary speed reduction being obtained through the gears 17 and 18. From the shaft 19 rotary motion is imparted to the car 6 through the elliptical gears 20 and 21. 110

Thus it will be seen that uniform rotation on the part of the motor gear 15 will result

in a variable rotation of the car 6, the elliptical gears 20 and 21 acting alternately to accelerate and retard the rotary motion of the car. The sensations excited in a passenger seated at any point in the car 6 by this continual variation of velocity, and more especially by the reversal of the acceleration, will be wholly different from those obtainable with the ordinary merry-go-round, or even one in which rotatable cars are used, driven at a constant velocity in the usual manner and will be decidedly novel and pleasurable. The mounting of the cars eccentrically has the advantage that every passenger in the car traverses a different path during the revolution of the main platform. This is best seen from the diagram, Fig. 8, in which the paths traversed by two persons seated at the points 30 and 31 are illustrated respectively by the full curve 32 and the dotted curve 33. In this case the car is mounted eccentrically and elliptical gears or other variable driving means, as in the construction shown in Figs. 1, 2 and 3, are used to transmit rotation to it. The two points chosen represent extremes, it being obvious that other points between these two will pass through distinctly different curves. Thus passengers in the car, not only traverse peculiar and irregular curves during one revolution of the main platform, but, by seating themselves in different parts of the car on successive rides or rotations of the main platform, experience a variety of different motions. This feature possesses the further and important advantage that the extent and rapidity of movement and change of velocity to which a person seated at or near the point of greatest eccentricity of the car is subjected will be very much greater than the similar forces experienced by a person seated at a point of less eccentricity. Persons in the same car may thus be treated to rides of different degrees of severity suited to their individual preference.

Through the use of cars of substantially circular configuration I attain a further novel effect, an illusion of collision at each revolution of the individual cars. The use of substantially circular cars mounted upon an eccentric axis furnishes a constant visual comparison for the passenger by which he is unconsciously led to appreciate that the curved peripheries of the cars are rapidly nearing a point of tangency or intersection and to anticipate an impending collision.

My invention is plainly capable of embodiment in various structures other than that above described, as for instance it is obvious that in place of elliptical gears for transmitting motion to the cars I may use lobed wheels, or other well known mechanical devices for producing a varying angular velocity from the uniform velocity of the

driving means, or I may use a driving means having a suitably variable velocity.

It may in some cases be desirable to use variable speed driving mechanism for rotating centrally mounted cars, in which case some but not all of the advantages of my invention are obtained. In other cases I may use eccentrically mounted cars driven at constant speed. Both of these conditions are within the scope of my invention. Examples of structures embodying eccentrically mounted cars driven at constant speed are shown in Figs. 4, 5, 6 and 7. In Fig. 4 I employ circular gears, driving connection being established from the motor 16^a through the bevel gears 14^a and 15^a, the construction otherwise remaining identical with that shown in the preceding figures.

In Figs. 5 and 6 I have shown how I may dispense with the individual motors for driving the several cars, making use of a stationary gear ring 23, meshing with gears 24, on shafts 25, carrying the cars 6, the latter being mounted eccentrically. Motion may be imparted to the main platform in the manner illustrated in Fig. 1, or the construction shown in Figs. 5 and 6 may be adopted, in which the motor 26 has its driving pinion 27 meshing with the circular rack 28 carried by the main shaft. In this case the operation is obvious; motor 26 causing the main platform to revolve through the agency of the circular rack 28, and the stationary gear ring 23 in turn causing independent rotation of the cars 6. The relative rate of rotation between the main platform and the individual cars has a marked effect upon the paths through which persons seated in the cars will pass. For instance, Fig. 9 illustrates two curves showing the paths of a passenger situated at the point 30 in an eccentrically mounted car when no elliptical gears are used. The curve 34 illustrates the result of a speed ratio of 1 to 1, that is, the car 6 makes one revolution while the main platform makes one revolution. Dotted curve 35 shows the effect of making the speed ratio 2 to 1, that is, having the car 6 rotate twice while the main platform rotates once. In Fig. 7 I have illustrated a structure similar to that shown in Figs. 5 and 6 but having a different ratio between the car driving gears and the central gear.

The construction illustrated in the first four figures where individual motors are used for driving the cars has the obvious advantage that the speed ratio may be easily altered or one car may be made to revolve faster than another.

Having thus described my invention, I claim:

1. An amusement device comprising a main rotatable structure, a passenger carrying car rotatably mounted thereon, and

means for rotating said car at a varying angular velocity.

2. An amusement device comprising a main rotatable structure, and a plurality of 5 passenger carrying cars of substantially circular configuration mounted thereon adapted to rotate about axes eccentric to said cars.

3. An amusement device comprising a main rotatable structure, a plurality of 10 passenger carrying cars rotatably mounted thereon, and means for rotating the latter at a constantly varying speed.

4. An amusement device comprising a main rotatable structure, a passenger carrying 15 car mounted thereon and constructed to rotate about an axis eccentric to said car, and means for rotating said passenger carrying car at a varying angular velocity.

5. An amusement device comprising a 20 main rotatable structure, a plurality of passenger carrying cars mounted thereon and constructed to rotate about axes eccentric to said cars, and means for rotating each 25 passenger carrying car at a constantly varying angular velocity independently of the other cars and of the main structure.

6. An amusement device comprising a main rotatable structure, a passenger carrying 30 car rotatably mounted thereon, and means including elliptical gears for rotating the cars.

7. An amusement device comprising a main rotatable structure, a passenger carrying car rotatably mounted thereon, and 35 means for rotating said car at a variable velocity, said means comprising a power device operating at a substantially constant speed and variable speed gearing for transmitting power from said power device to 40 said car.

8. In an amusement device a main rotatable structure, a passenger carrying car rotatably mounted thereon, a motor carried by the said main structure, and means includ-

ing elliptical gears for imparting rotation 45 from said motor to the said passenger carrying car.

9. In an amusement device, a main rotatable structure, a plurality of passenger carrying cars rotatably mounted thereon, and a 50 plurality of motors mounted on said main structure, one for rotating each of said cars.

10. An amusement device including a main rotatable structure, a passenger carrying car rotatably mounted thereon and 55 means for rotating said car, said means acting alternately to accelerate and retard the rotary motion of the car.

11. In an amusement device, a motor, a main rotatable structure, a passenger carrying car rotatably mounted thereon, a main shaft coincident with the axis of rotation of the said car and adapted to be rotated by said motor, a countershaft adjacent to said main shaft and parallel therewith, means 65 for transmitting motion from the main shaft to the countershaft, a sleeve on said main shaft rigidly attached to said passenger carrying structure, and driving means between said sleeve and countershaft. 70

12. In an amusement device, a motor, a main rotatable structure, a passenger carrying car rotatably mounted thereon, a main shaft coincident with the axis of rotation of the said car and adapted to be rotated by 75 said motor, a countershaft adjacent to said main shaft and parallel therewith, means for transmitting motion from the main shaft to the countershaft, a sleeve on said main shaft rigidly attached to said passenger carrying structure, and an elliptical gear on 80 said countershaft and a corresponding elliptical gear on said sleeve meshing with the elliptical gear on said countershaft. 85
